METHOD AND APPARATUS FOR REMOVING
BARK FROM TIMBER BY MEANS OF
FLUID JETS

Karl Johan Karlström, Thurbo, Hedemora, Sweden, assignor to Wikmanshytte Bruks Aktiebolag, Wikmanshyttan, Sweden, a corporation of Sweden

Application June 26, 1933, Serial No. 677,758
In Sweden July 30, 1932

6 Claims. (Cl. 144—208)

Various methods of removing bark from timber or pulp wood have been suggested, the means generally used for this object being machines with rotating knives or cutters, or barking drums within which the logs are placed, the removal of the bark being effected by the tumbling and abrading action of the logs upon each other, or the action of barking irons in the drum upon the logs, when rotating the drum. Barking by means of knives entails a considerable loss of wood, say 10-12% of the solid wood of the timber. It is true that the use of a barking drum does not entail any considerable loss of wood, but then there arises another drawback, the rubbing action of the blocks upon each other or against the barking irons, causing bark or other impurities to be forced into superficial cracks in the logs. This is a great disadvantage, when the timber is to be used in the manufacture of wood pulp. The bark removing machines and the barking drums have one disadvantage in common, i. e. great costs, both considering procuring and running expenses.

It has also been suggested and attempted to use fluid jets for the removal of the bark, but the attempts hitherto made have not proved successful, inasmuch as it has proved hard or even impossible to remove the bark, especially when handling fresh cut timber or timber cut during any other season than the sap-time. In those cases the bark is tightly cemented to the wood and the loosening effect of the fluid jet will be merely partial or even none at all.

My present invention relates to a method for barking timber by means of fluid jets, said method in practical operation having proved highly successful, the results being excellent even from economical points of view.

The invention is characterized by the following features. At first, the non-barked timber by means of hot water or steam is heated to a suitable temperature below 100° C. whereupon the timber is immediately subjected to a quick cooling action by means of water or any other suitable fluid. The timber thus prepared is subjected to the action of one or more powerful fluid jets, directed crossways against the timber and caused to move along the length of the same. Preferably, during the action of the jets the timbers are fed slowly along and at the same time imparted an intermittent turning movement, turning a certain angle for each step, with the object of facilitating the admittance of the jet to the whole surface of the timber.

Previously, attempts have been made to heat

the wood in order to loosen the bark. These attempts were carried out in closed containers and to high temperatures, more than 100° C., and after the heating the timber was allowed to cool slowly. In this procedure it appeared that the bark loosened by the heat, fastened anew during the cooling, the cause probably being that the resinous matters or other adhesives, which cement the bark to the wood, and which had softened during the strong heating, regain their former state during the slow cooling period, thus causing the bark to stick anew. In this case it is impossible to remove the bark by means of water jets.

Thus, it is evidently a matter of great importance that the wood is floated or soaked in water or any other cooling medium of comparatively low temperature immediately after the heating procedure.

By this proceeding the following advantages are attained:

(1) The timber is cooled quickly, which prevents the heat latent in the superficial wood and in the bark from drying the resinous matters or other adhesives, and consequently also prevents said resinous matters or adhesives from cementing the bark to the wood anew.

(2) The bark, having been brought into a mellow or loosened condition by means of the heat, will readily absorb fluid, which also contributes to the easy removal of the bark.

(3) The treatment with cooling fluid causes strains in the layer of bark and the superficial wood layer, which strains also have a profitable influence upon the loosening of the bark from the wood.

In the following specification I have set forth a description of a practical form of the invention, reference being made to the accompanying drawing, in which an apparatus for carrying out the method is schematically illustrated. Fig. 1 represents a vertical section along line I—I in Fig. 2, Fig. 2 is a plan view of the apparatus. Figs. 3 and 4 illustrate a longitudinal section and an end view respectively, of a preferred form of an apparatus for treating the timbers with hot water previous to the removal of the bark and Figures 5 and 6 are respectively side and plan views showing a log transported by conveyors.

The apparatus in question comprises a number of containers, 1, 2, 3, 4, 5, 6, within which the logs to be treated are placed, the containers being provided with covers. In case the preparatory treatment involves the use of steam these covers only need to be placed loosely on the containers,

no pressure being introduced. The covers being brought into place, steam is introduced into the containers through pipes at the bottom, and the temperature is allowed to rise to about 70-90° C.

5 According to the hardness of the bark, i. e. if the timbers have previously been floated or not, the temperature is maintained during 3-6 hours. Immediately upon this heat-treatment follows a water-treatment of the timbers, cold water 10 being washed over the timbers or the timbers being drenched in water.

This water causes the timbers to be lifted to the upper level of the container (Fig. 1 showing this moment of the treatment) from where they 15 are transmitted to carriers 7 and 8, feeding the timbers to the obliquely placed diverting members 9 and 10 respectively, each of which leads the timber to a feeding arrangement. By this feeding arrangement the timbers at a constant 20 velocity are fed vertically down to the bark removing apparatus proper. The feeding arrangement consists of a container 11, from the walls of which alternately stretch a number of inwardly sloping shelves 12 placed on different levels and 25 sloping alternately from two opposite sides towards the middle of the container, as shown in Fig. 1. This figure shows the logs 13 at the moment, when they are about to leave the respective shelves to be brought over to other shelves, 30 where they are caused to move in a direction opposite to their former movement. The lowest shelf of the apparatus carries the logs to the barking table 14. Each of the two barking tables shown consists of planks 15, 16, arranged in 35 groups, the planks of each group being placed at a certain distance from each other. Between the planks of each group extend endless chains 17, running over chain wheels and designed to move continuously. The chains are provided with 40 catches 18, placed at a certain distance from each other and designed to catch the logs, when leaving the feed arrangement, and carry them along. According to Fig. 2, in a container 26 are arranged 45 two barking or washing tables 14, one of which is designed to take logs from carrier 7 and the other from carrier 8.

The logs, as they are fed along over the tables 14, are subjected to the action of powerful jets of water, from nozzles 19 and 20, directed transversely against the logs and moved sideways in the length direction of the log. Thus the jets effectively remove the bark, and as the logs are periodically turned through an angle during the feeding movement, their entire surface will be 55 acted upon by the jets and the bark will be uniformly removed.

The catches 18 are placed so far apart, that there is ample time for finishing the barking of one log before the next log is brought into bark-60ing position. As shown in the drawing the washing table 14 is placed at an angle, rising from the point where the log enters upon the table, the rising angle being adapted to prevent the log from constantly rolling on the table when brought 65 along by the catches. However, as mentioned, above, it is to be noted, that the log must periodically turn through an angle, the intervals of time allowing the barking jets to be brought to work upon the whole surface of the log when the log is 70 moving along the washing table. For this object the table is provided with upwardly extending pins or other obstacles 28 placed at equal distances apart and each causing the log to turn through an angle during the movement along the 75 table. Having passed the washing table, the log

is entirely stripped. Then it is brought over to the carrier 21, by which the logs are conveyed to a washing drum 22. In this drum possibly remaining rudiments of bark or other impurities are removed. However, the use of the washing drum 5 is not always necessary. By way of example, the washing drum may be dispensed with in case the wood is to be used in the manufacture of sulphate pulp or bleached sulphite pulp.

When leaving the washing drum, the logs by 10 means of a carrier 23 are brought to the controlling—or check—table 24. From the check-table a carrier 25 transports the logs to the chipping machine.

Evidently, the method and apparatus described 15 above may be varied as to the details, without departing from the range of the invention.

The present method offers many profitable features compared to bark removing methods hitherto in use. As one of the most important features 20 the method in practical use will turn out much cheaper than former methods and, at the same time, it affords extraordinarily good results, as 25 with a careful handling of the apparatus, no wood will be wasted.

These profits to a great extent depend on the preparatory treatment mentioned above, i. e. the heating of the timber immediately followed by a quick cooling action, a procedure which loosens the bark from the wood and prevents any re-cementing of the bark to the wood. The heating being carried out at comparatively low temperatures the expenditure of heat and consequently the fuel consumption will turn out relatively low. As another consequence of the low 35 temperature, the design of the heat treatment containers may be of the simplest and plainest kind.

Using temperatures above 100° C., would mean 40 work under pressure, and in this case the containers regarding strength, tightness etc. must be designed and manufactured with utmost care. Moreover, the expenditure of heat and the fuel consumption then would be high enough to render the method unpracticable from economical points 45 of view. Besides the risk is always at hand, that the wood easily shows a brown colour. In case the wood is to be used in the manufacture of pulp, this means a brown colouring, i. e. a deterioration of the pulp.

Figs. 3 and 4 show another modification of 50 an apparatus for preparatorily treating the logs with hot water. The log container is denoted with the figure 30. A pump 31 by means of a conduit 32 is connected with the inside of the 55 container, another conduit 33 leading the water to the distributive pipes 34, arranged above the container. In this manner there may be effected, during a sufficient time, a washing of the logs with hot water. The hot washing being completed, the pump is connected to a cold water conduit, thus spouting cold water over the logs in order to attain the desired quick cooling action.

I claim:

1. A method for removing bark from timber 60 by means of fluid jets, consisting in subjecting logs with bark attached to a heat treatment, rapidly cooling said logs immediately after said heat-treatment by means of any suitable fluid, and subjecting said logs soon after the cooling 70 step to the action of powerful fluid-jets so as to remove the bark, previously softened and loosened by the preceding treatment with heat and cooling fluid.

2. A method for removing bark from timber, 75

consisting in preliminarily heating the logs by means of steam to a temperature of at most 100° C., immediately after said treatment drenching and quickly cooling the logs by means of water or other fluid, feeding the logs thus treated slowly along and exposing them along their whole length to the action of powerful fluid jets, directed crossways towards said logs, and causing said logs during such treatment to intermittently turn through an angle in order to expose all parts of the log surface to the action of the jets.

3. An apparatus for removing bark from logs, consisting of a number of containers with means for supplying heating and cooling agents to said logs with the bark attached, one or more washing tables, means for conveying said logs onto said tables, endless carriers combined with the washing tables and provided with catches for moving the logs along said tables, said washing tables being provided with upstanding projections in the way of said logs, so as to cause the logs to intermittently turn through an angle while being fed forward, nozzles arranged in front of said washing tables, said nozzles being adapted to be

moved to and fro in the lengthwise direction of the logs.

4. An apparatus as claimed in claim 3, characterized in this that each washing table consists of a number of longitudinal supports arranged in groups, the supports of each group being arranged at a certain distance from each other, the space between the supports of each group containing said endless carriers provided with the catches and said catches being spaced at such a distance from each other that there will be ample time for completing the removal of the bark from one log before the feeding of the next log begins.

5. An apparatus as claimed in claim 3, characterized in this that the washing tables are arranged with a slope, rising in the direction towards the nozzles.

6. Apparatus as claimed in claim 3, characterized in this that the two washing tables are arranged within each container, said log conveying means being arranged to convey the logs to each washing table from one of the heating containers, and diverting members provided for carrying over the logs from said conveying means to the washing tables.

KARL JOHAN KARLSTRÖM.
